UNITED STATES PATENT OFFICE.

GEORGE W. BICKERTON, OF YOUNGSTOWN, OHIO.

WINDOW-GUARD.

1,380,932.

Specification of Letters Patent.

Patented Feb. 17, 1920.

Application filed January 31, 1919. Serial No. 274,270.

To all whom it may concern:

Be it known that I, GEORGE W. BICKERTON, a citizen of the United States, residing at Youngstown, in the county of Mahoning and 5 State of Ohio, have invented certain new and useful Improvements in Window-Guards, of which the following is a specification.

This invention relates to a device for guarding windows and more particularly 10 street car windows and has for its object the production of simple and efficient means whereby the guard may be securely attached to the window casing also means of allowing the same to be swung downwardly.

15 Another object of this invention is to provide an elongated eye member of the guard which operates in conjunction with a lower bracket member thereby forming a hinge when the guard is swung downwardly also 20 making it impossible to remove the window guards from the bracket member which is attached to the window frame.

With these and other objects in view, this 25 invention consists of certain novel combinations, constructions and arrangements of parts, as will be hereinafter fully described and claimed.

In the accompanying drawings:

Figure 1 is a front elevation view of the 30 window guard.

Fig. 2 is a vertical end view of the same indicating by outline direction of the window guard when removed from its fastenings and swung downwardly.

35 Fig. 3 is a vertical end view of the device showing elongated eye in conjunction with the lower bracket member which is attached to the window frame.

Referring to the accompanying drawings 40 by numerals, it will be seen that the device for guarding windows, comprises a guard 1 said guard 1 being constructed of a plurality of horizontal bars 2 spaced apart, said horizontal bars 2 being merged with 45 perpendicular end bars 3.

By referring to Fig. 1 it will be seen that I have shown said window guard 1 installed so as to guard a series of windows 4, 5 and 6 which is a common arrangement of windows 50 provided in street cars and other similar vehicles.

At the upper corners of the window guard 1 are located projections 7, said projections being extensions of the upper horizontal bar 2, each of said projections rests 55 within a strap-shaped hook 8 which in turn

is securely attached to the window frame 9 by any ordinary means. The lower portion of the window guard 1 is held in position by means of an upturned hook 10 which is an 60 extension of the lower end of the end bars 3, said hook 10 passes through openings 11 of a bracket 12 which is in turn securely fastened to the window frame 9.

It will be noticed by referring to Fig. 2 or 65 3 that this bracket 12 has the lower portion 13 turned out at right angles to the plane of the window frame 9.

When it is desired to lower the window guard 1 it will be seen by referring to Fig. 70 2 that the window guard is raised until the projections 7 will clear the upper end 14 of the strap shaped hook 8. When the window guard 1 swings downwardly as indicated by the outline 15 in Fig. 2, the hook 10 turns 75 as a hinge in the opening 11 of the bracket 12. When installing it will be noticed the bracket 12 should be placed far enough up on the window frame 9 to allow the guard hook 10 to travel upward far enough to 80 allow the bar 2 to pass over point 15 of the strap shaped hook 8.

When it is desired to securely fasten the window guard 1 to the window frame so as to guard against unauthorized removal the 85 lower hook 10 is formed with an extended arm 16 as shown in Fig. 3 thereby making an elongated eye of the hook 10.

It is obvious that various modifications and changes may be made, and the right is 90 reserved to all such as do not depart from the spirit and scope of my invention.

What I claim is:

1. In a device of the class described, a 95 window guard member, comprising a plurality of horizontal bars spaced apart, vertical bars forming the ends of said window guard member, projections of the upper horizontal bar extending beyond the ends of said guard member, hooks secured to the 100 window frame, said hooks supporting the above mentioned projections and guard, brackets fastened to the lower portion of the window frame, said brackets provided with openings into which hook members of the 105 vertical end members substantially as described for the purpose set forth.

2. In a device of the class described, having in combination with a window, window frame and guard, upturned hooks securely 110 attached to said window frame, horizontal projections at the upper corners of said

guard member, said projections formed to rest in said hooks, lower bracket members fastened to the lower portion of the window frame, provided with holes, the upturned hooks of the guard formed to fit within said holes substantially as described for the purpose set forth.

3. In a device of the class described, a series of window guard members, each comprising a plurality of horizontal bars spaced apart, vertical bars forming the ends of said guard members, projections of the upper horizontal bar extending beyond the ends of

said guard members, said guards secured to the window frame by means of upper hooks 15 and lower brackets which form common supports for two adjacent guard members, each of said vertical bars having a hooked extremity which enters a hole in that lower bracket by which the bar is supported. 20

In testimony whereof I affix my signature.

GEORGE W. BICKERTON.
